UNITED STATES PATENT OFFICE.

WILLIAM ALBERT RAMSEY, OF CHARLOTTE, NORTH CAROLINA.

GARMENT DRIER.

Application filed August 6, 1925. Serial No. 48,548.

To all whom it may concern:

Be it known that I, WILLIAM ALBERT RAMSEY, a citizen of the United States, and a resident of Charlotte, in the county of 5 Mecklenburg and State of North Carolina, have invented a new and useful Garment Drier, of which the following is a specification.

The object of my invention is to provide 10 a novel, efficient, inexpensive and portable apparatus for drying garments for use in cleaning or tailor establishments. I attain these and other objects of my invention by the apparatus illustrated in the accompanying 15 drawing, in which:

Figure 1 is a perspective view of my invention in use;

Fig. 2 is a side elevation of a modified form of my invention; and

20 Fig. 3 is a horizontal section on line 3—3 of Fig. 2.

Like characters of reference designate like parts throughout the several views.

Referring to the accompanying drawings, 25 I provide a skeleton box or frame 1 having a screen covered hinged lid 2. The frame is provided with base 3 which supports the electric fan 4. I provide a circular wire frame 5 fastened in any suitable manner on lid 2 and to which is attached a plurality of springs 6 carrying the wire clothes pins 7. I provide an L-shaped garment supporting rod 10 secured in upright position by braces 8. Rod 10 and box frame 1 are mounted 30 on castors 9. I also provide a series of clamps 11 secured to rod 10 and in turn holding the electric cord 12 which is connected to the electric fan at one end and carries a plug 13 for connecting it with a 35 suitable source of electric current, at the other end. I provide a suitable eye 14 on the upper end of rod 10 to which in turn is secured a chain 15 and a spring device 16 terminating in an eye or hook 17 to which the conventional clothes hanger H may be 40 attached to support any desired garment G. I fasten clothes pin 7 to spaced portions of the hem or lower portion of the garment G to hold it in spread position to permit the 45 current of air from fan 4 to freely circulate through it. In a modified form of my invention substantially the same elements are utilized but a slightly modified framework is used. As both forms of the invention include castors the devices are readily portable.

In using the device, in the case of a dress, the dress is hung on a conventional clothes hanger and the hem of the dress is attached to a series of clothes pins which are attached to the springs anchored on the ring device attached to the lid of the frame so as to hold the skirt in a spread open position.

In drying trousers, the bottom portion of the legs of the trousers are attached to conventional clip trouser hangers which are attached to springs depending from the cross rod of a conventional garment hanger which is suspended in turn from the spring attached to the L-shaped rod. The waist of 70 the trousers is fastened in spread open position by the several clothes pins carried by the springs on the ring device. This arrangement permits the fan to circulate air 75 freely through the garments and thus to quickly dry them and to remove the odor of gasoline or other fluid used in cleaning the garments.

What I claim is:

1. In a garment drier, the combination of 80 a skeleton frame having a base to support an electric fan, an L-shaped rod for supporting the garment over the frame, braces securing said rod to the frame, a screen-covered hinged lid on the frame, a ring device anchored on the frame, means for suspending one end of the garment from the end of the L-shaped rod, and means for fastening the other end of the garment to the ring-shaped anchoring device.

2. In a garment drying device for use in 85 cleaning establishments, the combination of a basket-like frame, a screen-covered lid on said frame, an L-shaped garment supporting-rod, braces for securing said rod in fixed relation to the frame, means for suspending one end of the garment to the L-shaped rod, means for anchoring the other end of the garment in proximity to the screen-covered lid, and an electric fan positioned 100 in the frame and arranged to discharge a current of air upwards through the garments.

3. In a garment drier, the combination of 105 a skeleton frame having a base to support an electric fan, an L-shaped rod for supporting the garment over the frame, braces securing said rod to the frame, a screen-covered hinged lid on the frame, a ring device anchored on the frame, resilient means for suspending one end of the garment from 110 one end of the L-shaped rod, and resilient

- means for fastening the other end of the garment to the ring-shaped anchoring device.
4. In a garment drying device for use in cleaning establishments, the combination of a basket-like frame, a screen-covered lid on said frame, an L-shaped garment-supporting rod, braces for securing said rod in fixed relation to the frame, resilient means for suspending one end of the garment to the L-shaped rod, resilient means for anchoring the other end of the garment in proximity to the screen-covered lid, and an electric fan positioned in the frame and arranged to discharge a current of air upward through the garments.

5. In a garment drying device for use in cleaning establishments, the combination of a basket-like frame, a screen-covered lid on said frame, an L-shaped garment-supporting rod, braces for securing said rod in fixed relation to the frame, resilient means for suspending one end of the garment to the L-shaped rod, resilient means for anchoring the other end of the garment in proximity to the screen-covered lid, an electric fan positioned in the frame and arranged to discharge a current of air upwards through the garments, and an electric plug and cord connected to the fan and clamps attached to the L-shaped rod for holding the cord. 25 30

WILLIAM ALBERT RAMSEY.
